PUMP JACK

Walter E. Cummins, Boulder City, Nev.

Application August 4, 1934, Serial No. 738,473

11 Claims. (Cl. 74—56)

This invention relates to improvements in pump jacks.

The general object of the invention is to provide a long stroke pump jack of novel construction.

5 Another object of the invention is to provide a pump jack wherein the jerk on the polish rod at the end of each stroke is eliminated.

A further object of the invention is to provide a pump jack which when disconnected from its 10 associated polish rod is completely portable.

Other objects and the advantages of this invention will be apparent from the following description taken in connection with the accompanying drawings wherein:

15 Fig. 1 is an end view of my improved pump jack showing it operatively installed on an oil well derrick;

Fig. 2 is a fragmentary side view of the pump jack;

20 Fig. 3 is an enlarged fragmentary vertical section through the device;

Fig. 4 is a section taken on line 4—4 of Fig. 3;

Fig. 5 is a section taken on line 5—5 of Fig. 3;

25 Fig. 6 is a section taken on line 6—6 of Fig. 3 on a reduced scale;

Fig. 7 is an enlarged fragmentary side elevation of the supporting sleeve member;

Fig. 8 is a top plan view of the parts shown in Fig. 7; and,

30 Fig. 9 is a fragmentary view similar to Fig. 3 showing the stroke adjusting collar.

Referring to the drawings by reference characters I have indicated my improved pump jack generally at 10. As shown the device 10 includes 35 a frame portion 12 which is supported by rollers 13 which operate on spaced tracks 14 provided on the floor of an oil well derrick 15.

Mounted on the frame 12 I provide a bowl portion 16 which includes side walls 17 and a bottom 18. The open top of the bowl 16 is shown as closed by a cover member 19 and in the bottom 18 of the bowl I provide a threaded aperture 20.

Extending downward from the bowl 16 I provide a hollow well portion 21 which includes side 40 walls 22 and a bottom 23 having an aperture 24 therein and concentric with the aperture 24 I provide a packing gland 25. The upper end of the well portion 21 is threaded as at 26 to engage the threads of the aperture 20 of the bowl 16.

45 Adjacent the upper end of the bowl 16 I provide an outwardly extending flange portion 27 to which the cover 19 is secured by bolts 28 and nuts 29.

The cover 19 includes an upwardly extending 50 hub portion 29' having an aperture 30 therein

which is concentric with the aperture 20 in the bottom of the bowl.

Extending upwardly from the cover 19 I provide a hollow guard member 31 which includes side walls 32 and a top wall 33 having a pair 5 of spaced apertures 34 therein. The lower portion of the guard 31 fits around the cover hub 29 and is shown as secured thereto by bolts 35.

Positioned in the bowl 16 I provide a supporting sleeve member 26 which includes an outwardly extending flange 37 at its lower end and has an aperture 38 therein which is concentric with the bowl aperture 20. In the lower surface of the flange 37 I provide a ball race 39 and concentric therewith in the upper face of the 15 bowl bottom 18 I provide a similar ball race 40. Positioned in the ball races 39 and 40 I provide a plurality of steel balls 41 which rotatably support the sleeve 36.

Surrounding the sleeve 36 adjacent the flange 20 37 I provide a bevelled ring gear 42 which is free from the sleeve and has the teeth thereof facing upward. In the lower face of the ring gear 42 I provide a ball race 43 and in the upper face of the sleeve flange 37 I provide a coaxial ball 25 race 44. Positioned in the ball races 43 and 44 I provide a plurality of steel balls 45 which rotatably support the ring gear 42 on the sleeve flange 37.

Surrounding the sleeve 36 above the ring gear 30 42 I provide a clutch collar 46 which is shown as secured to the sleeve 36 by a key 47. In the lower face of the clutch collar 46 I provide a recess 48 and in the upper face of the clutch collar I provide a similar recess 49.

35 Adjacent the upper face of the clutch collar 46 I provide a bevelled ring gear 50 which like the ring gear 42 surrounds the sleeve 36 and is free from the sleeve. The teeth of the ring gear 50 face downward. In the upper face of 40 the ring gear 50 I provide a ball race 51. Secured to the cover 19 by bolts 52 and depending therefrom I provide a bearing collar 53 having a ball race 54 in the lower face thereof which is concentric with the ball race 51 of the ring gear 50. 45 Positioned in the ball races 51 and the ball race 54 I provide a plurality of steel balls 55.

Positioned in the aperture 38 of the sleeve 36 I provide a square threaded stem 56 having an aperture 57 therethrough. At its upper end the 50 stem 56 extends above the sleeve 36 and includes a reduced threaded hub 58 by means of which a cap member 59 is secured to the stem. The lower portion of the stem 56 extends downward and at its lower end the stem includes a reduced threaded 55

hub 60, by means of which a disk member 61 is secured to the stem.

To prevent the stem 56 from turning a pair of opposed keys 62 are secured to the side walls 22 of the well 21 as by rivets 63. The keys 62 are positioned in recesses 64 provided in the stem disk 61 (see Figs. 3 and 5).

Mounted on the sleeve 36 I provide a plurality of pins 65 having frusto-conical rollers 66 rotatably mounted thereon. The pins 65 and rollers 66 extend radially towards the center of the sleeve aperture 38 and are arranged in spiral form to conform to the spiral of the stem thread and the rollers 66 fit in between the threads of the stem. Thus it will be seen that when the sleeve 36 is rotated the rollers 66 will force the stem 56 to move either upward or downward depending on the direction the sleeve is rotated.

Positioned in an aperture 67 in the bowl 16 I provide a drive housing 68 which is shown as secured to the bowl by bolts 69. Mounted in the housing 68 I provide an anti-friction roller bearing 70 having a shaft 71 journalled therein. The shaft 71 extends into the bowl 16 and has a beveled gear 72 secured thereto which meshes with both the ring gear 42 and the ring gear 50. Secured adjacent the opposite end of the shaft 71 I provide a worm gear 73 which meshes with a worm pinion 74 secured to the armature shaft 75 of an electric motor 76. Positioned in the recess 49 of the clutch collar 46 I provide a clutch ring 77 which is split as indicated at 78 (see Fig. 6).

Secured to the ring gear 50 I provide a downwardly extending pin 79 which is positioned between the ends of the clutch ring 77. Adjacent one end of the clutch ring 77 I provide an enlarged portion 80 having an inwardly tapered cam face 81.

Positioned in the recess 48 of the clutch collar 46 I provide a clutch ring 82 which is similar to the clutch ring 77 and the like parts thereof are indicated by similarly primed reference numerals.

Positioned in a vertical recess 84 in the sleeve 36 I provide a clutch operating bar 85. The bar 85 is vertically movable in the recess 84 and intermediate its length includes an outwardly extending enlarged cam portion 86 which is vertically movable in a recess 87 provided in the clutch collar 46.

Rotatably mounted on the bar 85 adjacent the upper end thereof I provide a roller 88 which extends above the upper end of the bar and rotatably mounted on the bar 85 adjacent its lower end I provide a similar roller 89 which extends below the lower end of the bar.

When the bar 85 is moved upward as shown in Fig. 3 and the ring gears are rotating the cam portion 86 of the bar engages the cam face 81 of the clutch ring 77 and as the clutch ring is being rotated in the same direction as the ring gear 50 by the pin 79 the cam face 81 will jam against the cam portion 86 of the bar 85 thereby rotating the sleeve 36 in the same direction as the ring gear 50. When the sleeve 36 is thus rotated it will through the medium of the rollers 66 thereon move the stem 56 upward.

When the bar 85 is moved downward the cam portion 86 thereof will engage the cam face 81' of the clutch ring 82 and will actuate the sleeve 36 in the same direction as the ring gear 42 as previously described in connection with the clutch ring 77. When the sleeve 36 is thus rotated it will through the medium of the rollers 66 thereon move the stem 56 downward.

The clutch operating bar 85 is shown as supported by a pair of opposed arms 90 (see Figs. 7 and 8). One end of each arm 90 is positioned in a recess 91 provided in the bar 85 and the opposite end of the arm terminates in a ball portion 92 which is positioned in an aperture 93 provided in an arm 94 which is integral with the sleeve 36 and extends therefrom. The ball portion 92 extends out of the aperture 93 slightly and is engaged by a spring 10 arm 95 which is secured to the sleeve 36 by a bolt 96.

When the stem 56 approaches the limit of its downward travel the cap member 59 thereon engages the roller 89 of the clutch operating bar 85 and as it continues to move downward it moves the bar 85 downward thereby moving the cam portion 86 of the bar out of engagement with the clutch ring 77 and into engagement with the clutch ring 82 whereupon the direction of rotation of the sleeve 36 is reversed, as previously described.

When the stem 56 approaches the limit of its upward travel the disk member 61 thereon engages the roller 89 of the clutch operating bar 85 and as it continues to move upward it moves the bar 85 upward thereby moving the cam portion 86 of the bar out of engagement with the clutch ring 82 and into engagement with the clutch ring 77 whereupon the direction of rotation of the sleeve 36 is reversed, as previously described. For lubricating the device 10 the bowl 16 and the well 21 are preferably filled with oil.

When the device 10 is used in combination with an oil well, as shown, the polish rod 97 which operates the oil well pump extends into the well through the packing gland 25 and is positioned in the aperture 57 of the stem 56. The polish rod 97 extends above the cap member 59 and a clamp member 98 is firmly secured to the polish rod by bolts 99 and nuts 100, (see Fig. 4). The clamp member 98 rests on the cap 59 thus the polish rod 97 is supported by the stem 56 and as the stem travels up or down the polish rod travels with it thereby operating the oil well pump.

For controlling the weight of the polish rod 97 I may provide a frame 101 which is supported on the bowl 16 and includes four spaced upright members 102. Mounted to slide vertically on each pair of uprights 102 I provide weighted member 103. Mounted on the frame 102 above the upper end of the dust cap 31 I provide a pair of spaced pulleys 104.

Each of the weighted members 103 have one end of a cable 105 secured thereto which extends upward over the pulleys 104 and then downward and into the dust cap 31 through the apertures 34 therein. The opposite ends of the cables 105 include eyelet portions 106 which engage hook portions 107 integral with the cap member 59.

In Fig. 9 I have shown a collar member 109 which is used to adjust the travel of the stem 56 when the full travel thereof is not desired. The collar 109 includes a central aperture 110 in which the stem 56 is positioned. The collar 109 further includes a radially extending threaded aperture 112 in which a threaded plug 113 is positioned. The plug 113 includes a reduced stem portion 114 on which a frusto-conical member 115 is positioned.

When the collar 109 is used it is positioned on the stem 56 at the desired distance below the cap member 59 and thereafter the threaded plug 113 is tightened to force the conical mem-

ber 115 into tight engagement with the adjacent threads of the stem 56. Thereafter, when the stem 56 moves downward the collar 109 engages the roller 88 of the clutch operating bar 85 instead of the cap member 59 as previously described.

For retaining the device 10 in an operative position coaxial with the polish rod 97 I have shown two pairs of standards 116 which are mounted on the derrick floor, one pair adjacent each end of the frame 12 outside of the rails 14. Extending across the track from one standard 116 to the other I provide an angle iron 117 which is suitably secured to the standards. Each 15 of the angle irons 117 are shown as removably secured to the frame 12 by bolts 118 and nuts 119.

In use as the disks 61 move upwardly oil passes below this disk through the recesses 64 and when the disk moves downwardly the oil again passes 20 through the recesses 64 and this in effect provides a dash pot construction whereby jar is eliminated.

From the foregoing description it will be apparent that I have provided a novel long-stroke pump jack which is simple in construction and 25 highly efficient in operation.

Having thus described my invention, I claim:

1. In a pump jack, a supporting frame, a well on said frame, a bowl arranged above and communicating with said well, a cover on said bowl, 30 a guard on said cover, said guard being hollow and said cover having a hole affording communication between the guard and the bowl, a sleeve in said bowl, anti-friction means to support said sleeve for rotation, a bevel gear mounted 35 to rotate on said sleeve and having upwardly directed teeth thereon, a second bevel gear spaced from said first bevel gear and mounted to rotate on said sleeve and having downwardly directed teeth thereon, anti-friction means to support said 40 bevel gears, a clutch housing between said bevel gears, said clutch housing including a portion keyed to said sleeve, a drive gear in constant mesh with both of said bevel gears, a pair of clutch members in said clutch housing, one of 45 said clutch members coacting with said lower bevel gear to clutch said lower bevel gear to the sleeve and the other clutch member serving to clutch the upper bevel gear to the sleeve, a threaded stem disposed in said well and said 50 bowl and movable into and out of said cover, thread members in said sleeve engaging the threads of said threaded stem, said threaded stem having a disk thereon at the lower end thereof movable in said well, means to prevent 55 rotation of said disk and said threaded member, said last mentioned means being disposed in said well, a cap on the upper end of said threaded member, a counter-weight attached to said cap, a clutch actuating member slidably mounted in 60 said clutch housing, said clutch actuating member projecting beyond the clutch housing at each end thereof and having a roller at each end, said clutch operating member when in raised position being adapted to clutch said upper bevel 65 gear to said sleeve and when in lowered position being adapted to clutch the lower bevel gear to said sleeve, the upper roller of said clutch actuating member when in upper position engaging said cap to shift the clutch actuating member 70 and the lower roller on said clutch actuating member when in lowered position engaging said disk to shift the clutch actuating member.
2. In a pump jack, a supporting frame, a well on said frame, a bowl arranged above and communicating with said well, a cover on said bowl, 75

a guard on said cover, said guard being hollow and said cover having a hole affording communication between the guard and the bowl, a sleeve in said bowl, anti-friction means to support said sleeve for rotation, a bevelled gear 5 mounted to rotate on said sleeve and having upwardly directed teeth thereon, a second bevel gear spaced from said first bevel gear and mounted to rotate on said sleeve and having downwardly directed teeth thereon, a clutch housing, 10 said clutch housing including a portion keyed to said sleeve, a drive gear in constant mesh with both of said bevel gears, a pair of clutch members in said clutch housing, one of said clutch members coacting with said lower bevel gear to clutch said lower bevel gear to the sleeve and the other clutch member serving to clutch the upper bevel gear to the sleeve, a threaded stem disposed in said well and said bowl and movable into and out of said cover, threaded 15 members in said sleeve engaging the threads of said threaded member, said threaded stem having a disk thereon at the lower end thereof movable in said well, means to prevent rotation of said disk and said threaded member, a cap 20 on the upper end of said threaded member, a clutch actuating member mounted in said clutch housing, said clutch actuating member projecting beyond the clutch housing at each end thereof, said clutch operating member when in raised 25 position being adapted to clutch said upper bevel gear to said sleeve and when in lowered position being adapted to clutch the lower bevel gear to said sleeve, the upper end of said clutch actuating member when in upper position engaging 30 said cap to shift the clutch actuating member and the lower end on said clutch actuating member when in lowered position engaging said disk to shift the clutch actuating member.

3. In a pump jack, a supporting frame, a rotatable sleeve on said frame, a pair of independent oppositely facing gears mounted to rotate on said sleeve, means to drive said gears in opposite directions, a clutch means operative to selectively clutch either of said pair of gears to said sleeve, 45 a threaded stem disposed in said sleeve and threaded means in said sleeve located between said gears and engaging the threads of said stem.

4. In a pump jack, a supporting frame, a sleeve rotatable in said frame, a pair of gears mounted 50 to rotate on said sleeve, means to drive said gears in opposite directions, a clutch housing, said clutch housing including a portion keyed to said sleeve, a pair of clutch members in said clutch housing, one of said clutch members coacting 55 with one of said gears to clutch said one gear to the sleeve and the other clutch member serving to clutch the other gear to the sleeve, a threaded stem disposed in said sleeve, threaded means in said sleeve engaging the threads of said 60 threaded stem, a clutch actuating member slidably mounted in said clutch housing, said clutch actuating member projecting beyond the clutch housing at each end thereof and having a roller at each end, said clutch operating member when 65 in raised position being adapted to clutch said upper bevel gear to said sleeve and when in lowered position being adapted to clutch the lower bevel gear to said sleeve.

5. In a pump jack, a supporting frame, a sleeve 70 on said frame, anti-friction means to support said sleeve for rotation, a gear mounted to rotate on said sleeve and having upwardly directed teeth thereon, a second gear spaced from said first bevel gear and mounted to rotate on said sleeve and 75

having downwardly directed teeth thereon, a drive gear for both of said first two gears, a clutch between said gears, said clutch including a portion keyed to said sleeve and a pair of clutch members, one of said clutch members coacting with said lower gear to clutch said lower gear to the sleeve and the other clutch member serving to clutch the upper gear to the sleeve, a threaded stem, threaded means in said sleeve engaging the threads of said threaded stem, and a clutch actuating member adapted when in raised position to clutch said upper gear to said sleeve and when in lowered position being adapted to clutch the lower gear to said sleeve.

6. In a pump jack, a supporting frame, a well on said frame, a bowl arranged above and communicating with said well, a cover on said bowl, a guard on said cover, said guard being hollow and said cover having a hole affording communication between the guard and the bowl, a sleeve in said bowl, anti-friction means to support said sleeve for rotation, a bevel gear mounted to rotate on said sleeve and having upwardly directed teeth thereon, a second bevel gear spaced from said first bevel gear and mounted to rotate on said sleeve and having downwardly directed teeth thereon, a clutch housing, said clutch housing including a portion keyed to said sleeve, a drive gear in constant mesh with both of said bevel gears, a pair of clutch members in said clutch housing, one of said clutch members coacting with said lower bevel gear to clutch said lower bevel gear to the sleeve and the other clutch member serving to clutch the upper bevel gear to the sleeve, means to operate said clutch members, a threaded stem disposed in said well and said bowl and movable into and out of said cover and threaded means in said sleeve engaging the threads of said threaded member.

7. In a pump jack, a supporting frame, a well on said frame, a bowl arranged above and communicating with said well, a sleeve in said bowl, anti-friction means to support said sleeve for rotation, a bevelled gear mounted to rotate on said sleeve and having upwardly directed teeth thereon, a second bevel gear spaced from said first bevel gear and mounted to rotate on said sleeve and having downwardly directed teeth thereon, a clutch housing, said clutch housing including a portion keyed to said sleeve, a drive gear in constant mesh with both of said bevel gears, a pair of clutch members in said clutch housing, one of said clutch members coacting with said lower bevel gear to clutch said lower bevel gear to the sleeve and the other clutch member serving to clutch the upper bevel gear to the sleeve, means to operate said clutch members, a threaded stem disposed in said well and said bowl and movable into and out of said cover and threaded means in said sleeve engaging the threads of said threaded member.

8. In a pump jack, a supporting frame, a sleeve rotatable on said frame, a pair of gears mounted to rotate on said sleeve, means to drive said gears in opposite directions, a clutch housing, said clutch housing including a portion keyed to said sleeve, a pair of clutch members in said clutch housing, one of said clutch members coacting with one of said gears to clutch said one gear to the sleeve and the other clutch member serving to clutch the other gear to the sleeve, a threaded stem disposed in said sleeve, threaded means in said sleeve engaging the threads of said threaded stem, said threaded stem having a disk thereon at the lower end thereof, means to prevent rotation of said disk and said threaded member, a cap on the upper end of said threaded member, a clutch actuating member projecting beyond the clutch housing at each end thereof and having a roller at each end, said clutch operating member when in raised position being adapted to clutch said upper bevel gear to said sleeve and when in lowered position being adapted to clutch the lower bevel gear to said sleeve, the upper roller of said clutch actuating member when in upper position engaging said cap to shift the clutch actuating member and the lower roller on said clutch actuating member when in lowered position engaging the disk to shift the clutch actuating member.

9. In a pump jack, a supporting frame, a sleeve on said frame, anti-friction means to support said sleeve for rotation, a gear mounted to rotate on said sleeve and having upwardly directed teeth thereon, a second gear spaced from said first gear and mounted to rotate on said sleeve and having downwardly directed teeth thereon, a clutch housing between said bevel gears, said clutch housing including a portion keyed to said sleeve, a drive gear in constant mesh with both of said first gears, a pair of clutch members in said clutch housing, one of said clutch members coacting with said lower bevel gear to clutch said lower bevel gear to the sleeve and the other clutch member serving to clutch the upper bevel gear to the sleeve, a threaded stem, threaded members in said sleeve engaging the threads of said threaded stem, said threaded stem having a disk thereon at the lower end thereof movable in said well, means to prevent rotation of said disk and said threaded member, said last mentioned means being disposed in said well, a cap on the upper end of said threaded member, a clutch actuating member slidably mounted in said clutch housing, said clutch actuating member projecting beyond the clutch housing at each end thereof said clutch operating member when in raised position being adapted to clutch said upper bevel gear to said sleeve and when in lowered position being adapted to clutch the lower bevel gear to said sleeve.

10. In a pump jack, a supporting frame, a well on said frame, a bowl arranged above and communicating with said well, a sleeve in said bowl, anti-friction means to support said sleeve for rotation, a bevelled gear mounted to rotate on said sleeve and having upwardly directed teeth thereon, a second bevel gear spaced from said first bevel gear and mounted to rotate on said sleeve and having downwardly directed teeth thereon, a clutch housing, said clutch housing including a portion keyed to said sleeve, a drive gear in constant mesh with both of said bevel gears, a pair of clutch members in said clutch housing, one of said clutch members coacting with said lower bevel gear to clutch said lower bevel gear to the sleeve and the other clutch member serving to clutch the upper bevel gear to the sleeve, a threaded stem disposed in said well and said bowl and movable into and out of said cover and threaded means in said sleeve engaging the threads of said threaded member, said threaded stem having a disk thereon at the lower end thereof movable in said well, means to prevent rotation of said disk and said threaded member, said last mentioned means being disposed in said well, a cap on the upper end of said threaded member, a clutch actuating member slidably mounted in said clutch housing, said clutch actuating member projecting beyond the clutch housing at each end thereof said clutch operating member when in raised position being adapted to clutch said upper bevel gear to said sleeve and when in lowered position being adapted to clutch the lower bevel gear to said sleeve.

being adapted to clutch the lower beveled gear to said sleeve, the upper end of said clutch actuating member when in upper position engaging said cap to shift the clutch actuating member and the lower end on said clutch actuating member when in lowered position engaging said disk to shift the clutch actuating member.

11. In a pump jack, a supporting frame, a well on said frame, a bowl arranged above and communicating with said well, a sleeve in said bowl, anti-friction means to support said sleeve for rotation, a bevel gear mounted to rotate on said sleeve and having upwardly directed teeth thereon, a second bevel gear spaced from said first bevel gear and mounted to rotate on said sleeve and having downwardly directed teeth thereon, anti-friction means to support said bevel gears, a clutch housing between said bevel gears, said clutch housing including a portion keyed to said sleeve, 15 a drive gear in constant mesh with both of said bevel gears, a pair of clutch members in said clutch housing, one of said clutch members co-acting with said lower bevel gear to clutch said lower bevel gear to the sleeve and the other clutch

member serving to clutch the upper bevel gear to the sleeve, a threaded stem disposed in said well, threaded members in said sleeve engaging the threads of said threaded stem, said threaded stem having a disk thereon at the lower end thereof 5 movable in said well, means to prevent rotation of said disk and said threaded member, said last mentioned means being disposed in said well, a cap on the upper end of said threaded member, a clutch actuating member slidably mounted in 10 said clutch housing, said clutch actuating member projecting beyond the clutch housing at each end thereof and having a roller at each end, said clutch operating member when in raised position being adapted to clutch said upper bevel gear to 15 said sleeve and when in lowered position being adapted to clutch the lower bevel gear to said sleeve, the upper roller of said clutch actuating member when in upper position engaging said cap to shift the clutch actuating member when in 20 lowered position engaging said disk to shift the clutch actuating member.

WALTER E. CUMMINS.
